(57) **CLAIM**

The ornamental design for an eyelash curler, as shown and described.

DESCRIPTION

FIG. 1 is a front elevational view of the eyelash curler, showing my new design;

FIG. 2 is a rear elevational view thereof;

FIG. 3 is a top plan view thereof;

FIG. 4 is a bottom plan view thereof;

FIG. 5 is a left side view thereof, the right side view being a mirror image thereof;

FIG. 6 is a bottom, right perspective view thereof;

FIG. 7 is a top, right perspective view thereof;

FIG. 8 is a front elevational view of the eyelash curler with the lid removed;

FIG. 9 is a rear elevational view thereof;

FIG. 10 is a top plan view therein;

FIG. 11 is a bottom plan view thereof;

FIG. 12 is a right side view thereof, the left side view being a mirror image thereof;

FIG. 13 is a bottom, right perspective view thereof;

FIG. 14 is a top, right perspective view thereof;

FIG. 15 is a front elevational view of the eyelash curler in use;

FIG. 16 is a rear elevational view thereof;

FIG. 17 is a top plan view thereof;

FIG. 18 is a bottom plan view thereof;

FIG. 19 is a right side view thereof, the left side view being a mirror image thereof;

FIG. 20 is a bottom, right perspective view thereof; and,

FIG. 21 is a top, right perspective view thereof.

The eyelash curler is shown with and without the lid for convenience of illustration.
